[57] CLAIM

The ornamental design for a computer mouse, as shown and described.

DESCRIPTION

FIG. 1 is a left side elevational view of a computer mouse showing my new design;

FIG. 2 is a right side elevational view thereof;

FIG. 3 is a bottom plan view thereof;

FIG. 4 is a rear elevational view thereof;

FIG. 5 is a top plan view of a first embodiment thereof;

FIG. 6 is a top plan view of a second embodiment thereof;

FIG. 7 is a front elevational view of a first embodiment thereof;

FIG. 8 is a front elevational view of a second embodiment thereof;

FIG. 9 is a perspective view of a first embodiment thereof; and,

FIG. 10 is a perspective view of a second embodiment thereof.

The left side, right side, bottom plan and rear elevational views of the second embodiment are identical to those views shown in FIGS. 1-4, respectively.
